AUXILIARY BEARING AND BRAKE ACTUATING MEANS FOR RAILWAY CARS

Alex Nicholas, Little Falls, N. Y.

Application March 8, 1945, Serial No. 581,606

1 Claim. (Cl. 246—169)

1

My invention relates to an auxiliary bearing for railway cars and I declare the following to be a full, clear, concise and exact description thereof sufficient to enable anyone skilled in the art to which it appertains to make and use the same, reference being had to the accompanying drawings in which like parts are represented by like characters throughout the specification.

The object of the invention is to provide a dust proof auxiliary bearing for railway cars or other like vehicles that will function automatically in the event that the journal of the car burns out or becomes destroyed.

Heretofore, when a hot box caused the journal to burn out, serious trouble ensued, especially if the train was proceeding at a normal rate of speed. Under these conditions the wheels of the train effected would go off the track and tear up the roadbed and derail other cars behind the one above mentioned.

With the present invention this trouble is eliminated. The train can proceed with safety until it is brought to a stop by the automatic setting of the air brakes, which forms part of the invention.

The auxiliary bearing is designed also to prevent dust and other foreign particles from reaching the bearing.

The object will be understood by referring to the drawings, in which

Fig. 1 is a central vertical section of the auxiliary bearings, showing their relation to the chassis of the car, parts being in full.

Fig. 2 is a side elevation, slightly reproduced size, showing a side elevation of the invention in connection with the chassis of the car, parts broken away and certain covers to the auxiliary bearings removed.

Fig. 3 is a detail view, somewhat enlarged, showing an auxiliary bearing and immediate parts broken away.

Fig. 4 is a detail view, reduced in scale, showing a perspective of one of the wheels employed in the invention.

Fig. 5 is a detail view, showing a perspective of a channel member employed, parts being broken away.

Referring more particularly to the drawings, the invention embodies specially designed wheels, hereinafter mentioned, which support a truck 1 disposed at either end of the railway car. Said truck 1 has side frames 2, 2 that carry a removable channel cross member 3 provided with overhanging depending lips 4, 4 at either end thereof to engage the contiguous sides of frames 2, 2.

2

A top cross beam or arbor 5 arched upwards towards its center portion is disposed directly above cross member 3 and is held yieldingly in its upper positions by a pair of coiled springs 6, 6 located at each end of arbor 5. Each of said coiled springs 6, 6 rests in the channel member 3 and are in alignment with frames 2, 2. The upper ends of springs 6 rest beneath the under surface of beam 5. Heads 10, 10 formed integral with the ends of beam 5 extend laterally to overlap the contiguous sides of frames 2, 2, whereby to hold beam 5 in place. Apertures 11, 11 in frames 2, 2 are enlarged slightly at their lower portions, as at 12, 12 to allow for the assembling of beam 5.

A cross strut or supporting beam 13 rests on beam 5 and is held in place thereon by king pin 14. Beam 15 is disposed lengthwise of the chassis. Pipe 16 which is part of the air brake system is supported by suitable bearings in struts 13 of the chassis 1.

A box or housing bearing 20 is formed integral at either end of each of the side frames 2, 2. The bearing 20 is flat on its top surface and round or cylindrical at 21 on its under surface, whereby to form an emergency journal. Said box bearings 20 extend in depth and are disposed in transverse relation to frames 2, 2. The connection of said frames 2, 2 with box bearings 20, 20 is at about the middle portion thereof.

Said box bearings 20, 20 form auxiliary journals which will support the chassis 1 of the railroad car in the event that axle 24 should burn out or break. The break occurs generally on its journal portions as at 25, 25. The outer edge of the open end of each of the box bearings 20 is formed at an angle. A cover 26 fitted thereto is hinged at its top part 27 to the like portion of box bearing 20 and serves as a closing member to the open end of box bearing 20. The box bearings, therefore, prevent dust and dirt from reaching the axles 25, 25 and immediate parts.

In the event that axle 24 should break at or near journal part 25 no harm would result for the reason that box bearings 20 would serve as a journal. Axle 24 ties one pair of wheels 36, 36 together. It has a close fit with bushings 37, 37 and they in turn have a close or tight fit with wheels 36, 36, whereby axle 24 and wheels 36, 36 turn together.

Each of the wheels 36 has a flange 37 to hold it to the tracks, not shown. Each has cast also on the outer lateral surface thereof a conical or bulging cap member 41. The bulged outward portion 45 of cap member 41 is provided with

a central aperture 46 of much larger circumference than that of box bearing 20, whereby portions 45 do not contact box bearing 20 under normal conditions. In the event, however, that axle 24 should break and let down box bearing 20, said bearing 20 will contact with the annular edge 47 of cap member 41, which then becomes a bearing on which bearing 20 will ride until the train comes to a stop.

The means for setting the breaks, not shown, when axle 24 burns out contemplates a bell crank lever 50 pivoted at 51 to upstanding bifurcated bracket 52 made integral or otherwise secured to the adjacent part of side frame 2 at the location of box bearing 20. A chain 53 connects the upper end of lever 50 with the releasing arm of air valve 54 mounted in the air pipe 16.

The lower end of bell crank lever 50 has a slot 56 formed therein for the projection therethrough of the reduced end 57 of lever or tappet 58 that is pivoted at 59 to the grooved head 60 of bolt 61. The lower end of bolt 61 passes down through a threaded aperture in the top part 62 of box bearing 20.

The free end of lever 58 rests in the grooved head 64 of bolt 65. Bolt 65 passes down through a hole in the top part 62 of box bearing 20 and is adapted to slide therein. A headed fusible wire member 66 connects the depending part 67 of bolt 65 within box member or bearing 20 to the lower part of box bearing 20 where it is held by head 68.

Coiled springs 70 yieldingly hold the several bolts 65 in upward position. In each instance said spring 70 presses upward at one end against the under surface of the head of bolt 65 and rests at the other end on the upper surface 62 of box bearing 20.

In the event that axle 24 becomes over heated, fusible member 66 will melt and, thereby, allow spring 70 to rock lever 58 and connected lever 50 to set the brakes as hereinbelow explained.

When axle 24 breaks the curved or bearing side of box 20 will fall down into engagement with the adjacent edge 47 of cap member 41, as above explained. Simultaneously bell crank lever 50 will come into contact with the bulging side 45 of cap member 41 which will rock it into dotted line position shown in Fig. 1. Said lever 50 will exert a pull through chain 53 on the releasing arm of air valve 54 to release the air pressure in pipe 16 to thereby release the brakes, not shown, whereupon a succeeding air pressure forces the brakes into clamping position with wheels 36 for stopping the train.

Chain 53 connecting the left hand bell crank lever, shown in Fig. 1 with the releasing arm of air valve 54 will pass through a suitable aperture made in beam 15 to reach its destination.

In operation, we may assume that axle 24 becomes broken at journal part 25, then and in that event the adjacent box bearing 20 will fall down and come into bearing position on the edge 47 of cap member 41, which in this instance will function as a bearing. Simultaneously, bell crank lever 50 will rock from full to dotted line position shown in Fig. 1, whereby to exert a pull on chain 53 to actuate the releasing arm of air valve 54. This will release the air pressure in pipe 16, whereby to allow the brakes to contact the wheels 36. A subsequent pressure of air will force the brakes into clamping position with wheels 36, whereby to stop the train.

Having thus described my invention what I claim as new and desire to secure by Letters Patent is as follows:

In an auxiliary bearing for railway cars, a chassis; wheels for supporting said chassis, cap members form on said wheels to provide auxiliary bearings; an axle connecting said wheels, box bearings attached to said chassis, said axle extending through and forming a normal support for said box bearings, said box bearings adapted to extend within said cap members to provide auxiliary bearings for supporting said box bearings upon failure of the normal support, levers pivotally mounted on said bearing box, a brake pipe having a vent valve mounted on said chassis, chains connecting said levers to said valve, and said cap members adapted to operate said levers upon failure of said normal support, whereby to rock said levers to exert a pull on said chains for opening said vent valve to set the brakes of the cars.

ALEX NICHOLAS.
